Primary Examiner — Andrew Kerr

(57) **CLAIM**

The ornamental design for an integrated bottle grip, as shown and described.

DESCRIPTION

FIG. 1 is a top perspective view of an integrated bottle grip showing my new design;

FIG. 2 is a bottom perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a right elevation view thereof; and,

FIG. 8 is a left elevation view thereof.

The broken lines showing of a bottle body and cap in FIG. 1-8 are included for the purpose of showing environmental structure and form no part of the claimed design.
